UNITED STATES PATENT OFFICE.

GUSTAVE O. DEGENER, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,276,185.

Specification of Letters Patent. Patented Aug. 20, 1918.

Application filed June 30, 1914. Serial No. 848,219.

To all whom it may concern:

Be it known that I, GUSTAVE O. DEGENER, a citizen of the United States, residing in New York city, in the county of New York 5 and State of New York, have invented certain new and useful Improvements in Combined Type-Writing and Computing Machines, of which the following is a specification.

10 This invention relates to a combined type-writing and computing machine in which by the mere striking of the numeral keys, numbers can be simultaneously written and computed, and is an improvement on my 15 application No. 801,109, filed November 15, 1913.

In the exemplification to which the present improvement is applied, at the striking of a numeral key to write a digit, an interponent is positioned so as to be capable of setting one of a series of index pins forming part of a valuating mechanism, whereby an extent of rotation is obtained corresponding to the particular numeral key struck. At the 25 same time, a normally primed or set starting mechanism is tripped, which completes the electric circuit to a motor by closing contacts therefor, and also operates a hammer to thrust the selected interponent forward, 30 and set the opposite pin.

At the end of the computing operation, resetting mechanism comes into play automatically to reprime the starting mechanism, so that it will be capable of initiating 35 a subsequent computing action. This operation necessitates the tentative breaking of the motor circuit, or, at least, returns to a normal ineffective position, the part of the starting mechanism which first made the 40 electric contact.

In order that the computing operation may be absolutely completed and the resetting mechanism surely finish its work, means is provided in the present invention where- 45 by the resetting mechanism delays the break- of the contact and the opening of the circuit to the electric motor, until such time as it has completed its own work and returned to a normal passive position. To do this, the 50 contact maker or circuit closer is placed in a position such that it will be under the control of the resetting mechanism, which is provided with an extension or arm to engage the same, and hold this contact maker

in its effective position while the resetting 55 mechanism is in action.

The contact maker in the present instance is operated from the locking mechanism, which normally holds the starting mechanism in its set condition. The locking mech- 60 anism for the starting mechanism has been modified and simplified in the present in- vention, while still retaining the same pos- 65 tiveness and surety of operation as hereto- fore.

Other features and advantages will hereinafter appear.

In the accompanying drawings—

Figure 1 is a fragmentary skeleton perspective view showing the connection of one 70 of the numeral keys to the computing mech- anism, and such of the computing mech- anism as is deemed necessary to illustrate the present invention. Further details of this computing mechanism, and the relation to 75 the parts shown herein may be had by refer- ence to my application above mentioned.

Fig. 1^a is a vertical section through a com- puting head taken from front to rear.

Fig. 2 is a vertical section taken from 80 right to left from the rear of the machine, showing the starting mechanism as set for action, with the contact maker in its passive position and the contacts spread apart with the circuit open.

Fig. 3 is a view of certain of the parts shown in Fig. 2, but after the locking mech- anism has been tripped, and the electric cir- 90 cuit to the motor completed by the contact maker.

Fig. 4 is a view similar to Figs. 2 and 3, but after the starting mechanism has been almost entirely reset in a position such that the contact maker might have returned to its normal position as far as the starting 95 mechanism is concerned, but in which the contact maker is held in its effective position by the resetting mechanism which at this time is in action, so that the circuit to the electric motor is still closed.

Fig. 5 is a view similar to Figs. 2 to 4, showing the parts a little farther along in their action, indicating how the starting mechanism is overset, so as to insure the en- gaging of the coöperating parts of the lock- 105 ing mechanism.

Fig. 6 is an aggregate perspective view of the parts of the locking mechanism and the

contact maker, showing them detached and disassembled with respect to each other.

Fig. 7 is a fragmentary section showing the normal relation of the resetting cam to the follower of the resetting mechanism.

Fig. 8 is a detail perspective view showing the relation of the index wheel to the spur wheel which drives it.

Fig. 9 is a detail perspective view of the computing wheel detent.

Referring more particularly to the separate parts of this invention as embodied in the form shown in the drawings, numeral keys 1 when depressed, in addition to operating the usual type actions of an Underwood typewriting machine to print the digits corresponding to the keys struck, each draw down on a link 2 to rock a bell crank 3. The bell crank 3 draws on a link 4, to rock a lever 5, which in addition to swinging a locking segment 6 into play, by means of a pin-and-slot connection 7, swings an interponent 8 into the path of a hammer 9, so that when the latter is actuated, the selected interponent 8 will set the opposite one of a series of index or valuating pins 10 suitably mounted in an index or valuating wheel 11. The pin set determines the extent of rotation of the index wheel 11, making it correspond with the particular numeral key actuated.

The index wheel 11 may be rotated from an electric motor 12, which drives a train of gearing including a motor shaft 13; a bevel gear 14 thereon meshing with a bevel gear 15. The bevel gear 15 is loosely mounted on a shaft 16, but is connected by a slip clutch 17 to drive the shaft 16. The slip clutch may comprise a hub 18 secured to the bevel gear 15, telescoping with which is a split cylinder 19 fast on the shaft 16. The split cylinder 19, forming one element of the clutch, embraces the hub 18 sufficiently closely to normally form a positive connection between the motor and the shaft 16. If, however, any of the computing mechanism should become deranged or clogged in its movement, the clutch formed of these parts will slip, preventing the motor 12 from being burnt out, or from driving the parts with sufficient force to break them.

The shaft 16 is provided with a bevel gear 20 meshing with a bevel gear 21 loose on a shaft 22. To connect the bevel gear 21 in driving relation with the shaft 22, it is provided with a toothed clutch 23, into engagement with which may be brought a corresponding toothed clutch 24, splined on the shaft 22. The shaft 22 is provided with a spur wheel 25, (Fig. 8), which normally rotates idly in a gap formed by the previously set pin of the series of index pins 10. The gap, however, is eliminated by the unsetting of this pin at the setting of the new pin, by means of an unsetter 26. These and

various other actions essential to a computing operation in this type of machine, are brought into play automatically at the striking of one of the numeral keys 1, by a starting mechanism indicated in general at 27, 70 which is normally primed or set for action.

This starting mechanism may include a shaft 28, having a pinion 29 meshing with a rack 30 on a bar 31. The bar 31 is normally under a tendency to move upwardly 75 under the traction of a tension spring 32. The movement of the bar 31, and hence the rotation of the shaft 28, are, however, prevented by a locking mechanism, indicated in general at 132.

The locking mechanism 132 may include a block 33, secured to the shaft 28, and having a squared shoulder 34 (Fig. 6), normally engaged by a pivoted latch 35, which is held to its work by a spring 36. That is 80 to say, when the spring 32 is tensioned, and the starting mechanism all primed or set for action, the parts will be in the positions shown in Figs. 1 and 2, with the latch 35 in engagement with the shoulder 34. 90

At the striking of a numeral key 1, however, the latch 35 is tripped, to permit an action of the starting mechanism. To do this, each of the links 4 is provided with an enlargement or shoulder 37, which engages 95 the universal disk 38, so as to move the same against the tension of a spring 39. Connected to move with the universal disk 38, there is provided a lever 40, which rocks about its intermediate pivot to thrust forward a tripper 41 against the tension of a spring 42. The tripper 41 bears, at its extreme end, a series of teeth 43, so as to enable it to more readily engage the projecting upper end 44 of the latch 35. 105

It will thus be seen that when a numeral key 1 is struck, it positions a selected interponent 8, and trips the starting mechanism 27. As soon as the starting mechanism is tripped, the spring 32 acts, drawing the bar 31 upward, and rotating the shaft 28 and all parts carried thereby. Among other parts swung around by the shaft 28, will be the block 33, which is secured thereto.

This block 33, in addition to forming a 115 part of the locking mechanism 132, also provides means for completing the circuit to the electric motor 12. To do this, the block 33, as will be seen by reference to Figs. 2 to 6, is cam-shaped to operate a circuit closer or contact maker 45. The contact maker 45 is provided with a following roller 46, which normally rests in a socket or depression 47 provided in the block 33. When, however, the shaft 28 rotates to carry 120 the block 33 around to the position shown in Fig. 3, the following roller 46 will be forced out of the socket 47, and swung by the cam surface 48 of the block, to the position shown in Fig. 3, against the tension of a 130

spring 45^a (Fig. 1), which acts through a link 45^b. This camming action will rock the contact maker 45 about its pivot 49, so as to swing the upper end thereof from the 5 position shown in Fig. 2, to the position shown in Fig. 3.

The upper end of the contact maker 45 carries a finger 50, which presses on one of a pair of contacts 51 and 52, so as to spring 10 them to the position shown in Fig. 3, whereby they will be brought into engagement with each other. These contacts 51 and 52 are connected to the ends of an electric circuit indicated at 53, which is connected to 15 a suitable source of power and to the electric motor 12. It will therefore be seen that the starting mechanism excites to action the normally inactive electric motor 12.

In addition to this, the starting mechanism 20 operates the hammer 9, to strike the key-selected interponent 8, and set the opposite pin 10. To do this, the shaft 28 is provided with a dog 54, which in swinging momentarily pulls on a draw rod 55 against 25 the tension of a spring 56, so as to slide a bar 57, and with it the hammer 9, to such a position that it will strike the interponent 8 and set a pin 10. At the same time, the pin unsetters 26, is forced by a cam 58 on 30 the shaft 28, to strike the particular pin 10 at the gap in the series of pins. A spring 59 draws a clutch shifter 60 to a position to, close the clutch 23, 24, as soon as the cam 58 moves from under a spring finger 35 61 provided on the clutch shifter 60.

We then have the circuit to the motor closed, the clutch 23, 24 closed, the previously set pin unset, and the new pin set, so that the spur wheel may drive the index 40 wheel 11 around until the gap left by the just set pin comes into register therewith. This rotation will be carried by a train of gearing (not shown), part of which is indicated at 62, to a master wheel shaft 63, 45 which drives, by means of a master wheel 64, the computing wheels of a totalizer or computing head 65 in the usual manner.

After the index wheel 11 has completed 50 an extent of movement determined by the distance of the set pin from the previously set pin, determined by the value of the numeral key struck, the motor 12 must be stopped, or, at least, disconnected from the computing mechanism, and the starting 55 mechanism reset for a subsequent computing operation. To do this, a rocker 66 is swung by a toe 67 thereon being cammed aside by the pins 10 as the wheel 11 rotates, so that an arm 68 thereon will engage a spring-pressed latch 69 on a clutch closer or shifter 70.

The rocker 66 is also provided with an arm 71, which at a swinging of the rocker, is brought into the path of the just set pin 65 10, so that as the latter comes around to its

home position, with the gap formed thereby in register with the spur wheel, it will swing the rocker 66 back to its original position, carrying with it the latch 69 and the clutch closer 70. The clutch closer 70 will force 70 one element 72 of a clutch into engagement with a second element 73, against the tension of a spring located therebetween. The clutch element 72 is splined on a shaft 74, and driven thereby, while the clutch element 73 is loose on the shaft, and will only be driven when the clutch element 72 is in mesh therewith. The shaft 74 receives its drive from the shaft 16, by means of a pair of meshing bevel gears 76 and 77, so that 80 it will be rotated during a computing operation, when the motor 12 is in action. The reason for closing the clutch 72, 73 is in order to actuate a resetting mechanism 78, which re-primes the starting mechanism 27, 85 and returns all the elements which have taken part in the computing operation to their normal positions.

For this purpose, the clutch element 73 has secured thereon a sleeve 79, on which is 90 provided a cam 80. The cam 80, when rotated with the sleeve 79, engages and operates a following roller 81 secured to one arm 82 of a double bell crank lever 83, so as to rock the latter against the tension of 95 a spring 84. The bell crank lever 83 is provided with another arm 85, which on the rocking thereof, will engage a projection or roller 86 provided on an extension 87 of the bar 31. It will thus be seen that as the cam 100 80 rotates with the sleeve 79, the bar 31 will be depressed, retensioning the spring 32, and through the rack 30 and the gear 29, returning the shaft 28 and all parts carried thereby to their normal positions.

As the sleeve 79 completes its rotation, a second cam 88 (Fig. 1) carried thereby, will engage the latch 69 and trip the same, permitting the return of the clutch element 72, under the push of its spring, to its normal disengaged position with respect to the clutch element 73. This, then, disconnects 110 and throws out of action the resetting mechanism after it has completed its action.

It will be seen that as the resetting mechanism operates to re-prime the starting mechanism, the shaft 28 will be rotated, first to bring the block 33 to the position indicated in Fig. 4, where the following roller 46 will be in register with the depression or socket 115 47. Under such circumstances, the contact maker 45, if nothing else intervened, might return to its normal position indicated in Fig. 2, and break the circuit to the electric motor 12. This is prevented, however, from 120 the resetting mechanism itself, so long as it remains in action.

To do this, there is provided on the double bell crank lever 83 of the resetting mechanism, an extension or arm 89, which, as the 130

bell crank lever 83 rocks, is arranged to engage a cam edge 90 provided on the contact maker 45, and normally lying in the path of movement of the extension 89. We then 5 have the contact maker held in its effective position when the parts assume the positions shown in Fig. 4.

Inasmuch as it is necessary to insure the latch 35 catching under the shoulder 34 of 10 the locking block 33, the starting mechanism is slightly overset to the condition shown in Fig. 5. Under such circumstances, the cam surface on the far side of the depression 47 15 may engage the following roller 46, and hold the contact maker in its effective position.

As soon, however, as the resetting bell crank 83 returns under the pull of the spring 84, to its normal position, the starting shaft 28 will return under the pull of 20 the spring 32 as far as the latch 35 will permit it, resetting all parts to their true positions. Under such circumstances, the roller 46 will register with the depression 47 in the position shown in Fig. 2, and the 25 arm 89, which delayed the opening of the contact, will return to its normal position, permitting the contact maker to allow the opening of the circuit to the electric motor 12 so that the motor will stop when the 30 friction of the parts driven idly by it overcomes its momentum as happens after a number of turns.

In addition to the other functions mentioned, the starting mechanism prevents a 35 relative traveling movement between the master wheel and the computing wheels of the totalizer 65, and unlocks the computing train in register with the master wheel. Considering this feature with reference to 40 Fig. 1^a, it will be seen that the master wheel 64 engages internally, in succession, each one of a series of computing wheels 91, the relative movement being effected in the present instance, by the totalizer 65 itself 45 being mounted to travel with the typewriter carriage, indicated at 92.

Each of the computing wheels 91 is provided with an external gear 93, which meshes with a corresponding gear 94, 50 mounted on a dial wheel 95. A tens-carrying train 96 is provided for each computing wheel, whereby a complete rotation of a lower computing wheel may be carried to the next higher computing wheel. This 55 tens-carrying mechanism acts similarly to that shown in my above-mentioned application, and need not be specifically described, except that it comprises a complete gear 97, meshing with a higher computing 60 wheel, and a mutilated gear 98, which may be driven from an associated barrel gear 99. Said barrel gear 99 is driven by the motor 12 through the shaft 74 as set forth in said application, with the result that the carrying over may be completed even after the 65

index wheel 11 has been arrested. A similar carry-over device is shown in my Patent 1,020,082, dated March 12, 1912.

The mutilated gear 98 is provided with a number of sockets or depressions 100, in 70 which may rest a locking or detent roller 101, there being one of these locking rollers for each of the computing wheels. Each locking roller 101 is mounted on a locking dog 102, which is normally pressed to its 75 work by a spring 103.

When a computing operation starts, the bar 31, as has been previously mentioned, is pulled up by the spring 32. The extension 87 thereof will likewise move up, carrying 80 with it a link 104, which is connected to swing an arm 105, so as to rock a shaft 106. This shaft carries, in register with the master wheel 64, an arm 107, which is at the same time a locking arm and an unlocking 85 arm. That is to say, it is provided with a tooth or locking lug 108, which is arranged to engage between the teeth of a rack 108^a carried by the frame of the totalizer 65. The arm 107 also has a beak 109, which is 90 in range to engage the locking dog 102 which happens to be in engagement with the particular computing train in register with the master wheel.

It will thus be seen that the totalizer 65 95 is locked from a traveling movement at the same time that the computing train in register with the master wheel is unlocked. The dog 102 is provided with a hook 110, which is engaged by the beak 109 as the 100 latter disengages the dog 102, and thereby holds the totalizer 65 in a trued position, and prevents the same from wiggling up and down while the master wheel rotates.

When the starting mechanism is reset or 105 reprimed as above described, the arm 107 will be returned to its normal position, permitting the totalizer 65 to take a step movement with the carriage 92, and also permitting the return of the locking dog 102 to 110 prevent accidental rotation of its associated computing train.

It will be noted in passing that each locking dog 102 is formed of a single strip of metal folded on itself in spaced relation to 115 form a casing in which its locking roller 101 is pivoted, and folded in close relation at its lower end to form a strong rigid structure at the location of the hook 110.

Variations may be resorted to within the 120 scope of the invention, and portions of the improvements may be used without others.

Having thus described my invention, I claim:

1. In a computing machine, the combination 125 with computing mechanism, of a motor for driving the same, including an electric circuit, connections between said motor and said computing mechanism, a rock-shaft, a spring tending to rock said shaft to make 130

said connections effective, locking mechanism for said shaft, including a block fixed on said shaft, said block controlling the closing of said electric circuit, and a latch engaging said block to thereby prevent said spring from rocking said shaft, to make said connections effective, and said block from closing said circuit.

2. The combination with a computing mechanism, of a starting mechanism for said computing mechanism, a motor for driving said computing mechanism, a circuit to said motor, a contact maker for said circuit, and locking mechanism for said starting mechanism arranged to operate said contact maker to control the closing of the circuit to said motor.

3. The combination with a computing mechanism, of starting mechanism for said computing mechanism, normally set so as to be sprung into operation to initiate a computing operation, a motor for driving said computing mechanism, a normally open circuit for said motor, circuit-closing means for said circuit, and resetting mechanism arranged to reprime said starting mechanism, and acting to maintain said circuit closed while it itself is in action.

4. The combination with a computing mechanism, of starting mechanism for said computing mechanism, a motor for driving said computing mechanism, a normally open circuit to said motor, a circuit closer for said motor, resetting mechanism for said starting mechanism, and automatic means for controlling said circuit closer from said resetting mechanism.

5. The combination with a computing mechanism, of starting mechanism for initiating a computing action of said computing mechanism, resetting mechanism for repriming said starting mechanism at the termination of a computing operation by said computing mechanism, a motor for driving said computing mechanism, and a circuit closer for said motor, under the control of both said starting mechanism and said resetting mechanism.

6. The combination with a computing mechanism, of a starting mechanism for initiating a computing operation of said computing mechanism, said starting mechanism including a rotatable shaft, locking mechanism for said computing mechanism including a block secured to said shaft and having a shoulder thereon, and a latch engaging said shoulder to lock said shaft and said starting mechanism against action, and resetting mechanism acting to overset said starting mechanism to insure the catching of said latch under said shoulder, and to secure said starting mechanism in a primed condition ready for a subsequent computing operation.

7. The combination with a computing mechanism, of a motor for driving said com-

puting mechanism, circuit-closing means for said motor, operating means for said circuit-closing means, automatic means operating at the termination of a computing operation to return parts displaced during a computing operation to a normal position including said operating means for closing said circuit, and means for maintaining said circuit-closing means in position to maintain said circuit closed during and by the action of said automatic means.

8. The combination with a computing mechanism, of a motor for driving said computing mechanism, circuit-closing means for said motor, operating means for said circuit-closing means effective during a computing operation of said computing mechanism, automatic means coming into play at the termination of a computing action of said computing mechanism, and delaying means controlled from said automatic means to take up the burden of holding said circuit-closing means in action to maintain said motor in action after the computing operation has been completed.

9. The combination with a computing mechanism, of a motor for driving said computing mechanism, a circuit to said motor, circuit-closing means for said circuit, resetting mechanism tending to enable the return of said circuit-closing means to its inactive condition, and automatic means coming into play while said resetting mechanism is in action, for delaying the opening of the circuit.

10. The combination with a computing mechanism, of a motor for driving said computing mechanism, a circuit to said motor, a pair of contacts for said circuit, a contact maker for bringing about the engagement of said contacts, means for shifting said contact maker, said contact maker having a cam edge thereon, means brought into play automatically by said computing mechanism at the termination of a computing operation, and an arm carried by said last-mentioned means, engaging said cam edge to maintain said contact maker in action.

11. The combination with a computing head having a series of computing wheels, of a detent individual to each computing wheel, a master wheel for driving said computing wheels, said master wheel and said computing wheels having a relative step-by-step movement to enable said master wheel to register successively with each of said computing wheels, and an arm for engaging said detents successively to disengage them individually from said computing wheels, said detents and said arm having co-operating hook portions to prevent up and down movements of said computing head while said master wheel is rotating.

12. The combination with a computing head having a series of computing wheels,

- of a master wheel for driving said computing wheels, said master wheel and said computing wheels having a step-by-step movement to enable said master wheel to register successively with each computing train including one of said computing wheels, a locking rack on said computing head, a series of detents for said computing wheels, an arm having a tooth to engage between the teeth of said rack to lock said computing head against traveling movement, and having a beak to engage individually with each of said detents to disengage said detents from their associated computing trains.
13. The combination with a computing head having a series of computing wheels, of a master wheel for driving said computing wheels, said master wheel and said computing wheels having a step-by-step movement to enable said master wheel to register successively with each computing train including one of said computing wheels, a locking rack on said computing head, a series of detents for said computing wheels, and an arm having a tooth to engage between the teeth of said rack to lock said computing head against traveling movement, and having a beak to engage individually with each of said detents to disengage said detents from their associated computing trains, said detents each having a hook thereon to engage said beak individually and prevent vibratory movements of said computing head while said master wheel is rotating.
14. The combination with a computing mechanism, of a starting mechanism for said computing mechanism, a motor for driving said computing mechanism, a circuit to said motor, contacts for said circuit, operating means controlled from said starting mechanism for applying pressure to said contacts to complete said circuit, and resetting mechanism for said starting mechanism, acting to relieve the pressure on said contacts by said operating means, at the same time applying other force to maintain said contacts in engagement while said resetting mechanism is in action.
15. In a computing machine, the combination with computing wheels, of a power drive for turning said computing wheels, said drive comprising an electric motor circuit, a controlling member for the computing mechanism including a rotatable shaft, a latch normally holding said shaft, means for releasing said latch, means for putting said shaft under the control of said latch and adapted to overthrow said shaft to insure making said latch effective, and connections whereby said shaft closes said circuit when so overthrown.
16. In a computing machine, the combination with computing wheels, of a motor for

driving said wheels comprising an electric circuit, a controlling member for the computing mechanism adapted to close said circuit, a latch normally holding said controlling member ineffective, means for releasing said latch, connections whereby said motor positively restores said controlling member to its normal ineffective position, and an extension of said connections for holding said circuit closed until the end of the restoring operation.

17. In a computing machine, the combination with computing wheels, of a motor for driving said wheels comprising an electric circuit, a controlling member for the computing mechanism adapted to close said circuit, a latch normally holding said controlling member ineffective, means for releasing said latch, connections whereby said motor positively restores said controlling member to its normal ineffective position against the tension of a spring and overthrows said member to insure that the latch will become effective thereon, and connections whereby the motor circuit is held closed during such overthrow.

18. In a computing machine, the combination with a traveling carriage, a totalizer comprising computing wheels, and a master wheel for turning said wheels in an order determined by said carriage, of a lock for holding said carriage against traveling, a motor for driving said computing machine, a controlling member for said motor, key-controlled means for making said controlling member effective, means positively operated by said motor for making said controlling member ineffective, and for positively unlocking said carriage, a motor circuit under the control of said controlling member, and means for positively holding said circuit closed until the carriage is unlocked.

19. The combination with computing mechanism, of a motor for driving said computing mechanism, a pair of electric terminals for controlling said motor, a key-controlled controlling member for closing the circuit, a rotatable shaft forming part of said controlling member, a cam on said shaft, and a follower co-operating with said cam to positively hold said terminals closed whenever said shaft is in its abnormal position.

20. The combination with computing mechanism, of a motor for driving said computing mechanism, a pair of electric terminals for controlling said motor, a key-controlled controlling member for closing said circuit, a rotatable shaft forming part of said controlling member, a cam on said shaft, a follower co-operating with said cam to positively hold said terminals closed whenever said shaft is in its abnormal position, a one-

- way latch normally holding said shaft forming part of said key-controlled member, and means for overthrowing said shaft to certainly put it under the control of said latch.
- 5 21. In a power-driven computing machine, the combination with a controlling member, of an electric motor circuit driving said machine, a pair of terminals making and breaking said circuit, key-controlled means for 10 starting said controlling member to close said circuit, means driven by said motor for resetting said controlling member, said means adapted to positively hold said circuit closed while so resetting said controlling 15 member, and motor-driven means for timing the breaking of said circuit.
22. In a combined typewriting and computing machine, the combination with computing wheels, of carry-over devices for said 20 wheels, a motor for driving said wheels and said carry-over devices, a normally open circuit driving said motor, a controlling member for the computing mechanism and controlling said circuit, means for positively 25 holding said circuit closed by said member until the end of a computation and for further positively holding it closed during the resetting of said controlling member, and connections for allowing the motor to run 30 idly after so resetting said controlling member, for operating the carry-over devices.
23. In a computing machine, the combination with an index wheel comprising settable pins, of keys for setting said pins, a controlling member, a motor circuit for driving said machine, an auxiliary member for holding said circuit closed, and connections whereby the set pin makes the motor effective 35 to reset the controlling member and makes said auxiliary member effective to hold the circuit closed to effect said resetting.
24. In a computing machine, the combination with a traveling carriage, of a totalizer

comprising computing wheels, a master wheel for turning said computing wheels 45 *seriatim*, a lock for holding said carriage against traveling movement, a motor for driving said master wheel, a controlling member for said motor, and positive means operated by said motor for interfering with 50 the stopping of said motor as determined by said controlling member for a period determined by a given rotation of the motor itself.

25. The combination with computing 55 mechanism adapted to compute a number, of a motor for driving said computing mechanism, a circuit controlling the activity of said motor, and controlling means for delaying the breaking of the circuit for a 60 period subsequent to the actual computing of the number *per se*, determined by a given rotation of the motor itself.

26. The combination with a digital computing mechanism, of a motor for driving 65 said computing mechanism, and controlling means for determining the extent of rotation of said motor such that it will rotate an extent proportionate to the digit computed, plus a fixed amount terminated due 70 to a fixed subsequent movement of the motor itself.

27. A detent having a roller for coöperation with a socketed computing wheel, said detent comprising a strip of metal bent on 75 itself in spaced relation to form a casing for said roller, and further converging in close contact to form an ample and rigid surface by which said detent may be engaged and moved relatively to said computing wheel and held in its moved position. 80
